UNITED STATES PATENT OFFICE.

THOMAS W. KIMBELL, OF NEW YORK, N. Y.

LATCH.

SPECIFICATION forming part of Letters Patent No. 232,509, dated September 21, 1880.

Application filed April 12, 1880. (Model.)

To all whom it may concern:

Be it known that I, THOMAS W. KIMBELL, a resident of New York, in the county of New York, in the State of New York, have invented 5 a new, useful, and important Improvement in Door-Locks, described in this specification.

My invention consists in an improvement upon that class of locks which are unlocked from the outside with a key, from the inside 10 by a handle, are locked when the door is closed, and are arranged to draw the bolts at the bottom and top of the door when being unlocked.

Figure 1 is a perspective view of the lock 15 and bolts on the inner side of a door. Fig. 2 is a rear view of the same, with the bolt partly drawn. Fig. 3 is a horizontal section of the same.

In the form of lock shown, A is the case. B 20 is a bolt. C is a device to draw the bolt, which has a cam, F, to turn in a recess in the bolt to draw it, a key-receptacle, d, a handle, E, and ears g g, for the attachment of the chains h h, by which the spring-bolts H I are operated. 25 K is a spring for retracting the bolt after it is drawn.

The case has a slot, l, for a button, m, to fasten the device C when the door-bolts are drawn and hold them back. The bolt has a 30 stud, n, to move in a groove, o, on the back plate, P, to center the bolt.

Changes in the details of construction and operation may be made within the scope of my

invention. For example, the device C may be placed on the other side of the bolt and the 35 bolt may be centered by a stud on the frame.

The lock is adapted to either a right or left hand door, as it can be placed either side up, to suit the door.

Having now described my invention, I 40 claim—

1. The combination of case A, having slot l and groove o, bolt B, having stud n, device C, having cam F and key-receptacle d, handle E, and ears g g, chains h h, bolts H I, spring K, 45 and button m, substantially as set forth.

2. The combination of case A, having groove o, bolt B, having stud n, device C, having cam F, key-receptacle d, handle E, and ears g g, chains h h, bolts H I, and spring K, substan- 50 tially as set forth.

3. The combination of a latch-case having a guide for the bolt, a bolt having a stud and a retracting-spring, a device having a key-receptacle on one side, a handle on the other, a 55 cam to move the bolt, and ears to connect bolts for the top and bottom of a door, substantially as described.

In testimony whereof I hereunto subscribe my signature, in the presence of two attesting 60 witnesses, on the 10th day of March, 1880.

THOMAS W. KIMBELL.
